UNITED STATES PATENT OFFICE.

JOSEPH KRATOCHVIL, OF BRIDGEVILLE, PENNSYLVANIA.

PAINTBRUSH.

Application filed September 14, 1922. Serial No. 588,143.

To all whom it may concern:

Be it known that I, JOSEPH KRATOCHVIL, a citizen of United States, residing at Bridgeville, in the county of Allegheny, 5 State of Pennsylvania, have invented certain new and useful Improvements in Paint-brushes; and I do hereby declare the following to be a full, clear, and exact description of the invention, such as will enable 10 others skilled in the art to which it appertains to make and use the same.

The object of the invention is to provide a brush suitable for house painting, kalso-mining or other broad surface painting or 15 coating particularly when applying a finish to a ceiling or other over-head object, whereby the overflow or drip from the brush bristles may be caught or trapped and thereby prevented from flowing on to the handle 20 of the brush to the discomfort and inconvenience of the operator and, at the same time, may be conserved and subsequently returned to the bulk or supply for use instead of being wasted, as under the ordinary conditions, and with these objects in view the 25 invention consists in a construction and arrangement of parts of which a preferred embodiment is illustrated in the drawing wherein;

30 Figure 1 is a side view of a brush showing in dotted lines ducts or conductors whereby the surplus or drip from the bristles is carried to the reservoir.

Figure 2 is a sectional view taken longitudinally of the same.

Figure 3 is a sectional view on the plane indicated by line 3—3 of Figure 2.

Figure 4 is a transverse sectional view on the plane indicated by line 4—4 of Figure 2.

The brush head 10 may be of any suitable form, of construction or dimensions to suit the purpose for which it is designed and the bristles 11 carried thereby may be similarly 45 made of any preferred material for the same reasons, with the inner ends thereof held in compact relation by any preferred form of binder 12, serving to present the same proper relation for the efficient application of paint 50 or other coating to a surface.

Carried by the head in peripherally bounding relation therewith and in outward-

ly spaced relation with the marginal bristles is a guard band 13 of leather, or metal, or like material adapted to maintain its 55 form while presenting and performing the functions of the outer wall of the channel 12 formed between the same and the plane of the binder, for the purpose when the brush is in up-tilted or inverted position, as 60 shown in the drawings, of catching any drip or overflow from the bristles and preventing such overflow from passing to the outer surface of the guard band and thence to the body of the head and to the handle or grip, 65 which is indicated at 14.

The grip or handle is preferably hollow or cavitated as indicated at 15, to form a reservoir and in order to provide for the detachment of this reservoir for the purpose 70 of discharging the accumulated liquid therein it is provided with an exteriorly threaded nipple 16 engaged with a threaded outlet bore 17 in the reduced shank portion 18 of the brush head, while leading to this outlet 75 bore from the channel 12 bounded at its outer side by said guard band 13 are ducts or conveyors 19, bored or otherwise formed in the head and serving to convey liquid entering the drip channel to the reservoir 80 for subsequent removal and return to the supply or stock for subsequent use.

What is claimed is:

A brush having a tapered head formed with a bristle receiving recess in the larger 85 end and stepped shoulders in the outer face of the wall of said recess, the other end of the head having a central threaded bore extending longitudinally therewith for a short distance, a removable hollow handle having a nipple threaded in said bore and communicating therewith, a band secured to the head on one of the shoulders and outwardly of the other shoulder to form the outer wall of a channel of which the inner 90 wall of the said other shoulder is the inner wall thereof, the head having oblique passages extending from the bottom wall of said channel into the inner end of the said threaded bore for discharging paint into said 95 100 nipple.

In testimony whereof, I affix my signature.

JOSEPH KRATOCHVIL.
